DOORLOCK

Application filed November 28, 1928. Serial No. 322,326.

This invention relates to the so-called jimmy-proof locks of the overhang type. My invention contemplates the provision of a simplified mechanism for projecting the bolt 5 of this type of lock into a suitable keeper and is particularly designed to minimize the number and the cost of the operating parts which enter into the construction of the lock.

The various objects of my invention will 10 be clear from the description which follows and from the drawing in which,

Fig. 1 is a front elevation of my improved lock as it appears in locking position on a door.

15 Fig. 2 is a rear elevation of the lock, the keeper being partly in section, and the cover plate and the parts connected thereto having first been removed.

Fig. 3 is a vertical section of the lock, taken 20 on the line 3—3 of Fig. 2, and

Fig. 4 is a horizontal section of one end of the same, taken on the line 4—4 of Fig. 2.

In that practical embodiment of my invention which I have illustrated by way of example, the casing 10 is provided with a compartment 11 for the lock operating mechanism and with a compartment 12 for the reception of the bolt, consisting of three spaced extensions 13, 14 and 15, said extensions being 25 cast preferably integral with said casing (Fig. 4). The extensions 13 and 14 are separated by a space as 16, while the extensions 14 and 15 are similarly separated and spaced apart by the space or slot 17.

30 It will be noted that the extensions 13 and 15 are closed at the top and bottom, respectively, by means of the respective closing walls 18 and 19 thereof continuous with the respective walls 20 and 21 of the casing 10. It will also be noted that all of 35 the extensions 13, 14 and 15 are closed at the ends thereof by suitable walls as 22, 23 and 24 respectively, but that the extensions 13 and 15 are also provided

40 with additional walls as 25 and 26, continuous respectively with the walls 22 and 24 and serving to partially close the otherwise open inner ends of the respective extensions.

45 The angle keeper 27 is designed to be fastened to the jamb 28 of the door frame by

means of suitable screws such as 29. Projecting from the flange 30 of the keeper and preferably integral therewith is a pair of spaced annular keeper members 31 and 32 which are preferably horizontally disposed 55 and so proportioned and arranged as to enter and fit into the spaces 16 and 17 respectively between the extensions of the casing. Said members are provided, respectively, with openings 33 and 34 through which the bolt 35 may pass to lock the keeper to the casing when said bolt is in its locking position.

The bolt 35 is curved about the center of rotation thereof and terminates in a disc 36 provided with spaced notches 37 and 38 in 60 the peripheral edge thereof. The arm 39 serves to connect the disc 36 to the bolt 35, said bolt, arm and disc being preferably cast in one piece. For supporting the bolt for rotation about the casing, I prefer to provide 65 a removable pin 40 entering the bearing opening 41 which passes partway through the outer casing wall 42 and thereby not showing on the exterior face of the casing. Said pin terminates in a reduced portion 43 adapted to 70 enter a suitable hole in the removable cover 44, the disc 36 being loosely mounted on said pin, and said pin being thereby removable from the bolt, the casing and the cover. This 75 construction provides economy of construction and allows quick and easy assembling of the parts. By making the pin 40 removable, I am also able, when necessary, to readily replace or repair the bolt or the pin, should 80 it become necessary to do so. It will be seen 85 that the pin is maintained in place by the cover 44 when said cover is secured to the casing by means of a suitable screw entering the threaded post 45, projecting from the 90 outer wall 42 of the casing.

The cover is maintained in proper position for holding the operating parts of the lock against separation from their supports by means of said screw which clamps the cover against the lugs 46, said lugs being of such 95 length that the cover does not touch the various operating parts of the lock and thereby allows movement thereof about their respective pivots while preventing movement of said parts off their pivots and thereby main- 100

taining the proper operative connection between said parts. The mechanism for rotating the bolt 35 will now be described.

Said mechanism includes the crank 47 preferably made of a single piece of material and provided with an elongated guide slot 48. One end of said crank is secured to the disc 36 as by means of a pin 49 while the other end of said crank is guided in its movement by the pin 50, permanently arranged in and operating in the slot 48.

For actuating the crank 47 to rotate the disc, I provide key controlled means and manually operable means, said means being respectively disposed on opposite sides of the lock. The key controlled means consist of a headed shaft 51 pivoted to the cover 44 and maintained in place by the head 52 on one end thereof and operating arms 53 and 54 on the other end thereof and arranged near the inner face of the cover. The arm 53 is of sufficient length to enter the upper enlarged portion 55 of the slot 56 in the crank 47 and thereby, to actuate said crank on the rotation of the shaft 51. The arm 54 is bent a sufficient distance towards the interior of the casing to engage the depressed portion 57 of the detent lever 58 which is pivoted to the casing about the pin 59. Since the shaft 51 is designed to rotate through a complete revolution in the locking operation and also, during the unlocking operation, it is desirable that the arm 54 also clear the crank 47.

Toward this end, the arm 54 is bent inwardly as previously described, so as to pass interiorly of the crank 47 when the shaft 51 is rotated and the depressed portion 57 of the lever 58 is made slightly narrower than the remainder of said lever on the edge nearest the cover 44 whereby the arm 53 does not engage said lever on the rotation of the shaft 51.

The end 60 of said lever 58 is urged by the spring 61 into the notches 37 and 38 respectively in the locked and unlocked positions of the bolt 35. Said spring is mounted upon a suitable post 64, one end 62 thereof abutting against the upper wall 20 of the casing and the other end 63 engaging the upper surface of the lever 58.

It will be seen that as the shaft 51 is rotated by means of a suitable key, the arm 53 engages the left edge of the enlarged slot 55 as viewed in Fig. 2 and carries said crank to the left, the crank being guided in its movement by the pin 50. As said crank moves, the disc 36 and the bolt 35 are rotated and the lock is thereby unlocked, provided that the end 60 of the lever 58 is removed from the notch 37. This is accomplished by the arm 54 which engages the depressed portion 57 of the lever and raises said lever out of a notch 37 at the same time that movement of the crank 47 is begun. As the shaft 51

is further rotated back to its initial position, the arm 53 leaves the notch 55 and the arm 54 passes to the right of the depressed portion 57. Further rotation of the shaft 51 brings the arm 54 to its lowermost position to the interior of the crank 47 while the arm 53 passes the cut out portion at the edge of the lever 58 whereby the parts may be returned to their initial positions wherein the arm 53 enters the slot 55 and the arm 54 is arranged to the left of the depressed portion 57, ready to raise said portion when the rotation of the shaft 51 is reversed to bring the bolt into locking position.

The manually operated means for actuating the bolt 35 consist of the knob 65 pivotally mounted in the outer wall 42 of the casing 10 and carrying at the interior end thereof, a bell crank lever 66 having an arm 67 adapted to engage the depressed portion of the lever 58 and a diametrically opposed arm 68.

Said arm 68 terminates in a bent portion 69 permanently arranged in the reduced portion of the slot 56 and spaced from the center of rotation thereof a sufficient distance so that the arm 54 does not interfere with said bent portion when the shaft 51 is rotated.

It will be seen that when it is desired to operate the bolt 35, the knob 65 is turned whereupon the arm 67 of the bell crank lever 66 raises the lever 58 out of the notch in the disc 36, freeing said disc for rotation by the crank 47 when the bent end 69 operates said crank.

It will also be noted that the bolt 35 is made of sufficient length to pass completely through the casing extensions 13, 14 and 15 and through the keeper lugs 31 and 32, the end 70 of said bolt passing into the casing at the point of connection between said casing and the extension 13 whereby the end of the bolt is nowhere exposed but a continuous solid bar of metal extends across the juncture of the door and the door frame.

It will further be seen that I have provided an extremely simple lock, capable of being economically manufactured in large quantities and adapted to be easily assembled and disassembled for replacement and repair.

While I have shown and described an illustrative embodiment of my invention, I do not wish to be understood as limiting myself to the particular structure shown and described since I intend to claim my invention as broadly as may be permitted by the state of the prior art and the scope of the appended claims.

I claim:

1. In a door lock, the combination of a casing having a cover plate, a keeper, a pair of parallel lugs each having an opening therein projecting from said keeper, extensions on said casing separated by a pair of parallel spaced openings therebetween, said openings being arranged to straddle the lugs of the keeper upon the closing of the door, a curved

bolt rotatably mounted in said casing and adapted to pass through the openings of the keeper and into said extensions in the locked position thereof, a disc integrally connected to said bolt, a removable pin passing through said disc on which said bolt is mounted, said pin having one of its ends mounted in the casing and the other end mounted in the cover plate, said disc having a pair of spaced notches formed on the circumference thereof, a spring-pressed lever mounted in said casing arranged to register with one of said notches at a time to maintain said bolt in one of its extreme positions, a post projecting from the interior of the casing, a crank having a pair of slots therein pivotally connected to said disc, one of said slots arranged to be engaged by said post to guide said crank in its movement, a knob rotatably mounted in the casing, a bell-crank-lever secured to said knob, one arm of said lever adapted to engage the lever and the other arm of the bell-crank-lever being bent to engage the other slot of the crank for actuating the bolt, and a pair of key controlled arms mounted on the cover plate, one of said arms being bent and being shorter than the slot-engaging arm of the bell-crank-lever to pass thereover for releasing the bolt, the other of said key-controlled arms arranged to enter the second slot of the crank for transmitting reciprocatory motion to the crank for rotating the bolt in both directions.

2. In a lock, a casing provided with hollow spaced extensions, an outer horizontal wall closing each of the outermost of said extensions, a keeper having a pair of annular horizontal spaced lugs projecting therefrom and adapted to enter the spaces between said extensions, a curved bolt pivoted to said casing and adapted to pass into said extensions and through said lugs in the locking position thereof, said bolt being in the form of a segment of a ring, the center of which is the center of rotation of said bolt, a disc on said bolt having a pair of spaced notches in the circumferential edge thereof, spring-pressed means pivoted to said casing and adapted to enter said notches for maintaining said bolt in the extreme positions thereof, a plate cover for said casing, a key-controlled shaft pivoted to said cover, a pair of diametrically opposed radial arms extending from said shaft, one of said arms being adapted to engage the notch-engaging means for removing said means from engagement with said disc on the rotation of said shaft by a key, a knob pivoted to the casing, a bell-crank-lever secured to said knob on the inside of the casing, one arm of said lever being adapted to operate said notch-engaging means, the other arm of said lever being bent toward the cover, a crank having a pair of slots therein secured at one end to said disc, a pin passing through one of the slots of said crank for guiding said crank in the movement

thereof, the bent end of the arm of said bell-crank-lever permanently engaging the other slot in said crank for actuating said crank to rotate said disc on the rotation either of said key-controlled shaft or of said knob.

3. In a lock, a casing, similar hollow parallel spaced extensions of the same size at one end thereof, each of said extensions being of substantially rectangular outline and symmetrically disposed relatively to said casing and each having closing side walls, a closing outer end wall at the outer end thereof, and a shorter inner end wall extending from the side wall toward the casing and providing an opening for the passage of a bolt into said extension, and parallel to the other end wall, a keeper having a pair of symmetrically arranged and parallel projecting lugs adapted to enter the spaces between said extensions, said lugs having openings therein for the passage of the bolt hereinafter mentioned, and said openings being elongated in the direction of the length of the casing, a bolt movable in an arc mounted in said casing and arranged to interlock with the lugs of the keeper, said casing when interlocked with said keeper presenting a substantially symmetrical structure about a horizontal center line and means to operate said bolt.

4. In a lock, a casing, a curved bolt terminating in a coaxially arranged disc, said disc having a pair of spaced peripheral notches therein, a removable pin mounted coaxially of the disc and having one end inserted in the outer wall of the casing, said pin engaging and revolvably supporting said disc, a cover plate for the casing, a reduced end on the pin entering the cover plate, a shoulder on the pin at the inner extremity of the reduced end, engaging the inner face of the cover plate and preventing removal of the pin until the cover plate is first removed, and key-controlled and manually operable means for rotating the disc including a crank having a guide slot near one end thereof and having a peripheral notch, a pin near the other end of the crank entering the disc for pivoting the crank to the disc, a post on the casing entering the slot for guiding the crank, and a key-controlled and manually operable member controlled from the outside of the casing entering the peripheral notch of the crank for sliding said crank on the post.

5. In a lock, a casing having a bolt compartment therein comprising a plurality of hollow spaced extensions, the outermost pair of said extensions being of substantially the same size and each having a closing outer end wall and a shorter inner end wall extending from one end of the casing toward the other end to partly close the extension whereby an opening is provided beyond the edge of the inner wall for the passage of a bolt, said walls being substantially horizontal and parallel, a keeper, lugs on said keeper adapted to enter

the spaces between said extensions and having non-circular openings therein elongated in the direction of the length of the casing, a curved bolt, means for pivotally mounting said bolt including a disc arranged coaxially of and at one end of the bolt, a member pivoted at one end to the disc for rotation and mounted at its other end for longitudinal slidable movement, and a bell crank lever for sliding the member.

6. In a lock, a casing, a curved bolt terminating in a notched disc concentric with and spaced from the bolt and pivoted to said casing, and means for rotating said disc in either direction to open and close the lock, comprising a one-piece crank having a rectangular guide slot near one end and one edge thereof, a pin connecting the other end of the crank to the disc, said crank having an operating slot independent of and spaced transversely from the guide slot and adjacent and between the ends of said guide slot, and at the same end but at the other edge of the crank, a post on the casing entering the guide slot, and a manually operable bell crank lever adapted to enter the operating slot for sliding the slotted end of the crank on the post while simultaneously rotating the other end of the crank, and a spring-pressed lever entering the notch of the disc and adapted to be removed from the disc notch by the bell-crank-lever.

7. In a lock comprising a casing, a keeper, lugs projecting from said keeper, said casing having extensions at one end thereof arranged to straddle said lugs, a bolt pivoted to the casing to move in a curved path and arranged to pass through at least one of said lugs when said bolt is in locked position, mechanism to operate said bolt, said mechanism including a reciprocating member associated with said bolt to rock the same on its pivot, a slot formed in said member, a spring-pressed, rotatably mounted arm mounted in the front wall of said casing entering said slot of the member, means extending from the inner wall of said casing for guiding said reciprocating member, a cover plate removably attached to the casing and serving to maintain the bolt against lateral displacement when said bolt is rocked on its pivot, key actuated rotatable means to operate the arm against the action of the spring for transmitting rocking motion to said bolt, and similar manually operable means to operate the arm.

8. In a lock, the combination of a casing, a keeper, lugs projecting from said keeper, said casing having spaced openings at one end thereof and adapted to straddle said lugs, a bolt movably mounted in said casing for interlocking engagement with said keeper, an oscillating member mounted in the casing and having its pivot near the other end of the casing, a lever operated from the indoor side of the casing and rotatably mounted in the front wall of said casing to move the bolt,

a cover plate detachably secured to the lock casing, a second lever operated from the outdoor side of the casing and rotatably mounted in the cover plate to rock the oscillatory member to move the bolt, spring means mounted in the casing for maintaining the first lever in one position before said lever is rotated to move the bolt to its locking position and maintaining said lever in another position after said lever has been rotated against the action of said spring, to retract said bolt into unlocked state, said first lever being in constant engagement with said oscillatory member while the second lever engages said oscillatory member once, at the time when the bolt is moved to its locked state and again, when said bolt is retracted to its unlocked state, and key operated means to rotate said second lever to operate the lock.

9. In a lock, the combination of a casing, a keeper, lugs projecting from said keeper, said casing having spaced openings at one end thereof and adapted to straddle said lugs, a bolt mounted in said casing to interlock with said lugs, mechanism to operate said bolt, said mechanism comprising a rocking member pivotally mounted in the casing, a lever rotatably mounted and operable from one side of the casing, a second lever coaxially mounted with the first one and operable from the other side of the casing, a knob mounted on one side of the casing to rock the first lever, to operate the bolt, key means arranged to turn the second lever from the other side of the casing, said second lever being adapted to be rotated through a complete revolution to engage the rocking member and to actuate the bolt, said rocking member being in engagement with the first lever at all times and out of engagement at certain times with the second lever.

10. In a lock, the combination of a casing, a keeper, lugs projecting from said keeper, said casing having spaced openings at one end thereof and adapted to straddle said lugs, a bolt mounted in said casing to interlock with the lugs, mechanism to operate said bolt, said mechanism comprising a rockingly mounted member having a pivot in said casing adjacent an end thereof, a cover plate detachably secured to the lock casing, said cover plate being adapted to maintain said bolt against lateral displacement in the casing, a lever rotatably mounted in the wall of the casing and being in constant engagement with the rocking member, a second lever rotatably mounted in the cover plate, said second lever being arranged to be rotated a complete revolution, thereby engaging the rocking member on its circular movement to actuate the bolt and being out of engagement, with said rocking member when the bolt is locked, and key operated means to rotate said second lever.

11. In a lock, the combination of a casing,

a keeper, lugs projecting from said keeper, said casing having spaced opening at one end thereof and adapted to straddle said lugs, a bolt movable in said casing for interlocking engagement with said keeper, a rockingly mounted member having its pivot adjacent the rear wall of the casing and at the other end thereof, a pair of oppositely arranged levers coaxially mounted to actuate said rocking member to move the bolt, one of said levers being in constant engagement with said rocking member and being partially rotated to move the bolt, the other of said levers being adapted to be rotated a complete revolution to actuate the bolt and being out of engagement with said member when the bolt is in its locked state.

12. In a lock, the combination of a casing, a keeper, lugs projecting from said keeper, said casing having spaced openings at one end thereof and adapted to straddle said lugs, a bolt movably mounted in the casing for interlocking engagement with said keeper, an oscillating member mounted in the casing and having its pivot near the other end of the casing, a first lever operated from the indoor side of the casing and rotatably mounted in the front wall of said casing to operate the bolt, a cover plate detachably secured to the casing, a second lever operated from the outdoor side of the casing and rotatably mounted in the cover plate, a spring actuated detent pivotally mounted in the casing and exerting pressure at all times on the first lever for maintaining said lever in one position before said lever is rotated to move the bolt to its locking position and maintaining said first lever in another position after said lever has been rotated against the action of said detent, to retract the bolt into unlocked state, said first lever being in constant engagement with said oscillating member while said second lever, during each revolution thereof, engages said oscillatory member intermittently to move the bolt, a knob mounted on one side of the casing and connected to the first lever to rock said first lever against the action of the detent in one direction, to move the bolt to its locked state, and in the other direction to retract said bolt into its unlocked state, and key-operated means to rotate said second lever to operate the lock.

JOHN HOLTZMAN.
